ABSTRACT: A power vacuum fuse for interrupting high voltage alternating currents. The fuse has one or more fusible, current-responsive elements spanning a pair of spaced electrodes adjacent the peripheries thereof. Leads to a high voltage line extend from the central regions of the electrodes, each of the electrodes being slotted from the central region to the periphery thereof to define a current path to each element which extends both radially outwardly and tangentially with respect to a central axis of the electrodes. The effect of the slotted electrodes is to apply a force to each element which expels it from between the electrodes upon melting of the element, such force having a tangential component which spins the arc established when all the elements are severed, thereby preventing the arc from swelling to preclude extreme volatilization of the elements and electrodes so that the circuit will be interrupted at the first natural current zero following severance of the elements.

HIGH VOLTAGE POWER VACUUM FUSE

This invention relates to improvements in power vacuum fuses and, in particular, to a vacuum fuse incorporating means for preventing the arc established during interruption from causing extreme volatilization of the fuse material.

One of the problems found in vacuum fuses in high voltage, high amperage applications is the extreme volatilization of the electrodes and current-responsive element or elements of the fuse when interruption is caused by high short circuit currents. Although a high vacuum condition may be maintained within the fuse prior to interruption, additional ions are made available to sustain an electric arc if substantial volatilization is permitted to occur at the time of interruption. Manifestly, complete interruption of the circuit is not effected until the arc is extinguished and, secondly, the prolonged presence of the arc presents a hazard which must be avoided.

It is, therefore, the primary object of this invention to provide a power vacuum fuse which will operate at voltages on the order of 600 volts and higher with assurance that an arc will not be long sustained within the fuse at the time that the fusible element or elements thereof are severed by a high short circuit current.

As a corollary to the foregoing object, it is an important aim of the present invention to provide a fuse as aforesaid which effects rapid movement of the arc upon establishment thereof to prevent the arc from dwelling and thereby causing extreme volatilization of surrounding material.

Furthermore, it is an important object of this invention to provide a fuse as aforesaid having electrodes between which a fusible element extends adjacent the peripheries of the electrodes, wherein such electrodes cause the current to apply a force to the element having both radially and tangentially directed components so that the element upon melting thereof will be expelled from between the electrodes by the force and the arc thus established will be moved along the electrodes in a spinning fashion by the tangential force component to prevent the arc from dwelling where initially established.

Another important object of the invention is to provide a fuse as aforesaid having a plurality of such current-responsive elements, wherein progressively longer paths for current flow from the central regions of the electrodes to successive elements are provided, and wherein such paths extend both radially outwardly and tangentially with respect to a central axis of the electrodes to effect the application of both radial and tangential force components to the elements.

Still another important object of the invention is to provide a power fuse as aforesaid in which the same components of the fuse construction may be utilized for different ampere ratings, with the exception of only the current-responsive element or elements which would be sized in accordance with the desired continuous current rating.

Yet another important object of the invention is to provide a vacuum fuse construction having novel means of connecting the fusible elements to the electrodes so that elements of any of a number of diameters (depending upon the desired rating) may be utilized with the same electrode configuration.

In the drawing:

FIG. 1 is a cross-sectional view of the power fuse showing the electrodes and the leads extending therefrom in elevation;

FIG. 2 is an enlarged, fragmentary view showing the electrodes in perspective;

FIG. 3 is a top plan view of the upper electrode on the same scale as FIG. 2;

FIG. 4 is a view half in cross section and half in elevation of the lower electrode on the same scale as FIG. 2;

FIG. 5 is a cross-sectional, detail view taken along line 5-5 of FIG. 2; and

FIG. 6 is a view like FIG. 5 showing a modification.

Referring to FIG. 1, the fuse has a cylindrical housing 10 provided with a sidewall 12 of insulating material. The housing 10 has circular, metallic end plates 14 and 16 closing the sidewall 12 to present a cylindrical chamber 18 therewithin. The chamber 18 is evacuated after assembly of the fuse, an evacuation tube 20 extending through the end plate 16 being

provided for this purpose. A vacuum in chamber 18 on the order of 10^{-16} to 10^{-18} Torr is established, and the chamber 18 is then sealed such as by pinching the tube 20 shut as illustrated. A conductive probe 22 in sidewall 12 is provided so that the vacuum in chamber 18 may be checked electrically.

A pair of upper and lower, disc-shaped electrodes 24 and 24a are disposed in chamber 18 in spaced, axially aligned relationship to each other. The two electrodes 24 and 24a are identical in configuration with one being inverted with respect to the other. Therefore, it will be understood that corresponding features of the two electrodes are designated by the same reference numerals with the addition of the "a" notation with reference to the lower electrode 24a.

The electrodes 24 and 24a have central regions 26 and 26a to which a pair of solid copper leads 28 and 28a are joined both mechanically and electrically at their respective lower and upper ends. As is clear in FIG. 4, the upper end of the lead 28a is flush with region 26a, the latter being axially bored and countersunk to receive the head of a flat head screw 27a which is threaded into a tapped, axial hole in the end of lead 28a. The lead 28 is joined to the electrode 24 in the same manner and extends outwardly from the housing 10 through the end plate 14, the lead 28 being connected to a high voltage line (not shown) to be protected by the fuse. The lead 28a from the lower electrode 24a extends through the end plate 16 and is also connected to the line to place the fuse in series therewith. Alternatively, the leads 28 and 28a may be silver soldered to the electrodes 24 and 24a and the screw holes omitted.

Three generally spiral slots 29, 30 and 31 in electrode 24 extend from the central region 26 thereof radially and tangentially outwardly to the circumferential periphery 32 of the electrode 24. The inner and outer terminations of the three slots 29, 30 and 31 are angularly spaced at intervals of 120° , and adjacent slots partially angularly overlap each other as is clear in FIG. 3.

Three fusible, rodlike elements 34, 36 and 38, which may be of copper composition, span the electrodes 24 and 24a and are disposed adjacent the peripheries 32 and 32a thereof generally alongside the slot 30. The elements 34, 36 and 38 are equally angularly spaced about the common central axis 40 of the electrodes 24 and 24a defined by their geometric centers. Three hollow bosses 42, 44 and 46 project from the upper surface of the electrode 24 and are aligned with three openings in the electrode 24 into which the upper end portions of the elements 34, 36 and 38 extend respectively. One of such openings 48 aligned with the boss 42 is revealed in FIG. 5, where it may be seen that the element 34 is of lesser diameter than the opening 48 and extends therewith completely through the electrode 24 and into the boss 42. To effect both an electrical and a mechanical connection, the boss 42 is crimped around the tip of the upper end portion of element 34, the other bosses 44 and 46 being likewise crimped around the upper tips of their respective elements 36 and 38. In similar fashion the bosses 42a, 44a and 46a on the electrode 24a are crimped around the lower tips of respective elements 34-38.

A cylindrical support spacer 50 of insulating material, preferably a ceramic substance, is interposed between the electrodes 24 and 24a and is disposed in coaxial relationship to the axis 40. The spacer 50 is radially inwardly spaced from the elements 34, 36 and 38, as is most clearly revealed in FIG. 1, and is useful in assembly operations.

A cylindrical, metallic shield 52 is coaxially disposed within housing 10 and is radially outwardly spaced from the electrodes 24 and 24a and radially inwardly spaced from the housing sidewall 12. The shield 52 is attached to the end plate 14 and extends into surrounding relationship to the electrode assembly to protect the sidewall 12 during interruption of the fuse, as will be discussed hereinafter.

The present invention is especially adapted for the protection of alternating current power lines having voltages on the order of 600 volts through the high voltage range. The leads

28 and 28a are connected to the line to be protected to place the elements 34, 36 and 38 in series with such line. FIG. 3 illustrates the current paths to the three elements 34, 36 and 38 which extend from the central region 26 of the electrode 24 around the slot 30. Identical current paths also exist between the central region 26a of the lower electrode 24a and the elements 34, 36 and 38, except that the direction of current flow is opposite during a given half cycle of the alternating current wave.

The current path along electrode 24 to the element 34 is represented at 54 and is a straight line from the inner termination of the slot 30 to the upper tip of the element 34 where the connection is made to the electrode 24. The current path to the element 36 is represented at 56 and follows the outer edge of the slot 30 until the latter diverges from a direct line to the element 36, at which point the path 56 follows a straight line from the bend in the slot 30 to the element 36. Similarly, the current path 58 to the third element 38 follows the slot 30 for approximately two-thirds of its length before traversing a straight line to the element 38. It may be appreciated, therefore, that the spiral configuration of the slot 30 forces the current paths 54, 56 and 58 to extend in both radial and tangential directions with respect to the central axis 40 in order to reach the respective elements by the shortest route. Furthermore, it is important to note that the current paths 54, 56 and 58 to the respective elements 34, 36 and 38 are progressively longer in length, as is clear from a study of FIG. 3.

When a short circuit or overload current flows through the fuse, the paths 54, 56 and 58 are necessarily traversed by the current to cause the current to apply electromagnetic forces to the three elements. The resultant force on the element 36 is represented by the vector R_1 , the resultant force on the element 36 is represented by the vector R_2 , and the resultant force on the element 38 is represented by the vector R_3 . Each of these vectors has both radial and tangential force components as is clearly illustrated in the vector diagrams included in FIG. 3. As each element 34, 36 or 38 melts, the presence of the resultant vector R_1 , R_2 or R_3 expels the element from between the electrodes 24 and 24a by ejection therefrom in a direction toward the shield 52 (FIG. 1). Thus, the melted material of the current-responsive elements is not permitted to remain between or on the electrodes where substantial volatilization thereof could occur when arcing across the electrodes is ultimately produced upon severance of all of the elements.

The tangential force components are identified P_1 , P_2 and P_3 and serve to spin the arc about the axis 40 to further reduce the volatilization of the fusible elements and also prevent excessive volatilization of the electrode material. This spinning persists until a natural current zero occurs following severance of the three elements. This action will now be explained in greater detail.

Besides the tangential force components P_1 , P_2 and P_3 , forces of mutual attraction between the elements 34, 36 and 38 are present prior to severance of the elements by the melting thereof. Thus, an attractive force exists between elements 34 and 36, a second attractive force exists between elements 36 and 38, and a third attractive force is in existence between elements 34 and 38. Therefore, the total force on element 34 is the vectorial sum of R_1 (including its tangential component P_1) and the mutual forces of attraction between element 34 and elements 36 and 38. It is believed that this total force on element 34 is the greatest total force experienced by any of the elements. This conclusion is reached since, prior to severance of any element, the forces of mutual attraction on the center element 36 cancel one another and the resultant mutual attraction force on the element 38 is the vectorial sum of the mutual attraction force between elements 34 and 38 and the mutual attraction force between elements 36 and 38, both of which are essentially in opposition to the force R_3 . In contrast to this, the force R_1 and the mutual attraction forces acting on element 34 are vectorially additive, resulting in a higher total force on element 34.

In accordance with the foregoing, it is believed that when the element 34 reaches a plastic state, due to the flow of short circuit or overload current therethrough, this element is severed first because of the higher total force acting thereon in a direction transverse to its length. This increases the currents through the remaining elements 36 and 38. The total force on the element 36 now becomes a vectorial combination of R_2 and the mutual attraction force between elements 36 and 38; therefore, the element 36 is the next to sever. With element 36 now severed, the entire current must flow through the single remaining element 38, which severs immediately due to the high force of R_3 acting thereon. The severance of all three elements occurs very rapidly and, if the short circuit condition occurs as the current wave is ascending, complete severance of all elements should be effected prior to the time that the current wave reaches the next natural current zero, with full interruption of the circuit occurring at the current zero point.

In order for interruption to occur, the arc that will be established across the electrodes 24 and 24a at the time of severance of the last element must be extinguished. Due to the presence of the tangential force component P_3 , the arc is forced to move along the periphery of the electrodes and is thus spun about the central axis 40. The presence of tangential forces to maintain the arc in motion is assured by the spiral configuration of the slots 29, 30 and 31, the latter serving to maintain a tangential driving force on the arc at all angular positions thereof to sustain the spinning motion. Therefore, substantial volatilization of the electrode material, as well as the elements 34-38, is precluded since the arc is prevented from dwelling where initially established. The spinning motion of the arc continues until the current zero is reached, whereupon extinguishment of the arc completes the interruption of the circuit.

As may now be appreciated, the material of the electrodes 24 and 24a should, as much as possible, be resistant to volatilization to minimize the generation of gaseous ions during interruption. Annealed copper is suitable as the electrode material and should be baked out at a sufficient temperature to remove occluded gases which could interfere with the interruption of the fuse.

Although three fusible elements 34-38 are illustrated herein, it should be understood that one or a plurality of such elements may be utilized in accordance with the continuous rating desired for a particular fuse application. In this respect, it is noteworthy that the construction of the fuse of the present invention is such that fuses of different ratings may be constructed utilizing the same basic components without modification, except for the number, size and material of the fusible elements themselves. The adaptation of elements of different diameters to a single electrode design is best illustrated in FIG. 5, where it may be seen that elements of different diameters may be inserted into the respective openings therefor in the electrodes. The opening 48 there illustrated would be of a diameter greater than the maximum diameter of the fusible elements to be utilized, and the internal diameter of the hollow boss 42 (prior to crimping) would be at least equal to such maximum diameter. If desired, as shown in FIG. 6, a ceramic insulating sleeve 60 may be inserted into an enlarged opening 48' to positively prevent contact of the element 34 with the electrode 24 beneath the upper tip of the element as it bends during severance.

Although the electrode configuration herein is one in which a plurality of generally spiral slots are employed, it should also be understood that other slotted electrode configurations could be utilized to establish the requisite radial and tangential force components. Regardless of the particular slot arrangement utilized, however, it is important that the radial and tangential force components produced as a result of the slotted configuration have sufficient magnitude to execute the element-ejecting and arc-spinning functions discussed above. Otherwise, the problem of excessive volatilization becomes acute, and the fuse would not be suited to the high voltage, high power applications for which the present invention is par-

ticularly adapted. Although the advantageous features of the fuse are useful at voltages as low as 600 volts, special need for the invention is particularly experienced at line voltages on the order of 5,000 volts and above.

Having thus described the invention, what I claim as new and desired to be secured by Letters Patent is:

1. A power fuse comprising:

housing structure having an evacuated chamber therein; a pair of spaced electrodes in said chamber; a fusible, current-responsive element extending between 10 said electrodes and electrically interconnecting the latter; and means for electrically connecting said electrodes with a current-carrying line to interpose said element in series with 15 said line, said electrodes having nonradial groove defining means therein configured to cause current flowing between said electrodes through said element to apply a force to the element in a direction to both a. expel the element from between the electrodes upon 20 melting of the element under short circuit current conditions and attendant establishment of an arc across the electrodes, and b. effect movement of the arc along the electrodes to 25 prevent the arc from dwelling where initially established or at any point thereon, each of said electrodes having an outer periphery, said connecting means being connected to a region of each electrode disposed centrally with respect to the periphery 30 thereof, the central regions of said electrodes being aligned to define an axis extending between the electrodes through said regions, 35 said element spanning said electrodes adjacent the peripheries thereof in spaced relationship to said regions and interconnecting opposed portions of the electrodes which are in closest relative spaced relationship, said force having components directed radially outwardly of said axis and tangentially thereof respectively, whereby 40 the force effects the expulsion of the melted element and the tangential component thereof imparts said movement to the arc and spins the latter about said axis.

2. The power fuse as claimed in claim 1,

said element being rodlike and having a diameter selected in 45 accordance with the desired continuous current rating of the fuse,

each of said electrodes having an opening therein adjacent the periphery thereof of a diameter greater than the diameter of the element that would be selected for the 50 maximum rating of the fuse,

said element having opposed end portions extending into respective openings,

each of said electrodes having means adjacent its opening connecting the end portion therein to the electrode.

3. The power fuse as claimed in claim 2,

each of said electrodes having a hollow boss thereon aligned with the opening therein for receiving the respective end portion,

the boss of each electrode being crimped around the 60 received end portion to present said end portion connecting means.

4. The power fuse as claimed in claim 1;

and a generally cylindrical support spacer of insulating

65

material disposed between said electrodes in coaxial relationship to said axis and radially inwardly of said element.

5. The power fuse as claimed in claim 1; and a shield radially spaced from said axis and disposed in surrounding relationship to said electrodes between the latter and said housing.

6. The power fuse as claimed in claim 1,

each of said electrodes having slot means therethrough presenting said groove means causing current to apply said force to said element, said slot means extending along an arcuate path from said region of each electrode outwardly to said periphery thereof and establishing a nonlinear path for current flow from said region to said element extending both radially outwardly of said axis and tangentially thereof to thereby effect application of said force to said element, whereby said force effects the expulsion of the melted element and has a tangential component which imparts said movement to the arc and spins the latter about said axis.

7. A power fuse comprising:

housing structure having an evacuated chamber therein; a pair of spaced electrodes in said chamber each having an outer periphery;

a plurality of fusible, current-responsive elements extending between said electrodes and electrically interconnecting the latter; and

means for electrically connecting said electrodes with a current-carrying line to interpose said elements in series with said line,

said connecting means being connected to a region of each electrode disposed centrally with respect to the periphery thereof,

the central regions of said electrodes being aligned to define an axis extending between the electrodes through said regions,

said elements being angularly spaced from one another with respect to said axis and spanning said electrodes adjacent the peripheries thereof in spaced relationship to said regions and interconnecting opposed portions of the electrodes which are in closest relative spaced relationship, said electrodes having nonradial groove defining means configured to cause current flowing between said electrodes through said elements to apply forces to respective elements having components directed radially outwardly of said axis and tangentially thereof to both

a. expel the elements from between the electrodes as the elements melt under short circuit current conditions, whereby an arc is established across the electrodes when all of the elements are expelled, and

b. spin the arc about said axis to prevent the arc from dwelling where initially established or at any point on the electrodes.

8. The power fuse as claimed in claim 7,

each of said electrodes having slot means therethrough presenting said groove means causing current to apply said forces to said elements, said slot means extending along an arcuate path from said region of each electrode outwardly to said periphery thereof and establishing progressively longer paths for current flow from said region to successive elements,

said paths extending both radially outwardly and tangentially of said axis to effect application of said force components to said elements.
